VEHICLE EMBLEM PLATE

Chester M. Kosiba, Baltimore, Md.

Application April 24, 1959, Serial No. 55,654

Term of patent 14 years

(Cl. D14—6)

Fig.1

Fig. 3

Fig. 1 is a front elevational view of a vehicle emblem plate, showing my new design;

Fig. 2 is a top plan view thereof; and

Fig. 3 is a sectional view of the same taken on line 3—3 of Fig. 1.

The dominant features of the design are shown in full lines.

I claim:

The ornamental design for a vehicle emblem plate, as shown and described.
